UNITED STATES PATENT OFFICE.

ALLEN A. RUSSELL, OF INDIANAPOLIS, INDIANA.

THRASHING-MACHINE.

SPECIFICATION forming part of Letters Patent No. 255,120, dated March 21, 1882.

Application filed May 31, 1881. (No model.)

To all whom it may concern:

Be it known that I, ALLEN A. RUSSELL, of Indianapolis, in the county of Marion and State of Indiana, have invented certain new and useful Improvements in Thrashing-Machines; and I do hereby declare the following to be a full, clear, and exact description of the invention, such as will enable others skilled in the art to which it pertains to make and use it, reference being had to the accompanying drawings, which form part of this specification.

My invention relates to thrashing-machines or grain-separators; and it consists in certain features of construction and combinations of parts, as will hereinafter be described, and pointed out in the claims.

In the drawings, Figure 1 is a perspective view of a separator constructed according to my invention. Fig. 2 is a view in longitudinal vertical section of said separator. Fig. 3 is an interior view of the concave, as viewed from the feed-board, with the thrashing-cylinder removed. Fig. 4 is an interior view, showing the upper portion or roof of the concave. Fig. 5 is an interior view, showing the concave as seen from the rear, looking toward the feed-board, with the thrashing-cylinder removed. Fig. 6 is a detached view, showing the fan-easing and its removable lower section. Fig. 7 is a detached view, showing the blast mechanism and its application to the straw-carrier. Fig. 8 is a detached view, showing the distributor or upper screen of the shoe. Fig. 9 is a detached view, showing the manner of and mechanism for adjusting the concave to and from the thrashing-cylinder.

The object of my invention is to provide a machine that can easily be arranged and adapted for thrashing oats, wheat, barley, clover, millet, timothy, flax, or other seeds.

A is the frame-work of the machine, to which all the working parts are attached. This frame may be of any suitable character or construction to suit the necessities of the case.

45 B is the thrashing-cylinder, the thrashing-teeth of which may be of any suitable character or construction.

The concave of my machine consists of series of inclined ribs upon the back, upper, and front portion and of toothed sections upon its lower or under portion.

When the machine is used for thrashing and hulling clover-seed the concave sections T T' T² (illustrated in Figs. 2, 3, and 4 of the drawings) are all employed, substantially as represented; 55 but when the machine is used for thrashing grain or other seeds the two front concave sections T at the foot of the feed-board and the middle back section, T², of the concave are removed, and a suitable number of the ordinary 60 thrashing concave sections are employed below and around the thrashing-cylinder. As regards the upper ribbed section, T', of the concave, (illustrated in Fig. 3 of the drawings,) it may be used for thrashing grain or it 65 may be removed, as desired.

My improved concave consists of a toothed cylinder and concave sections T T' T², arranged to form a central feed-opening, and formed with ribs R, converging upwardly from said 70 opening, a concave over the cylinder provided with ribs converging rearwardly, and a concave section in rear of the cylinder arranged to leave a discharge-opening, S, at each end, and formed with ribs diverging toward said 75 openings, so that a double spiral conductor is formed by the hulling-sections, and the material, as it is carried around by the cylinder, is continuously fed by the spiral ribs endwise from the middle toward the discharge-openings S 80 at the rear side of the cylinder.

When it is desired to use the machine for thrashing grain or other seeds than clover the rear and middle concave sections, T² T', (illustrated in Fig. 2,) and the two lateral front concave sections (illustrated in Fig. 4 of the drawings) are removed. So, also, may the upper concave section (illustrated in Fig. 3) be removed, 85

and a sufficient number of any suitable spiked or toothed thrashing concave sections be added 90 below or around the thrashing-cylinder. I prefer to construct my concave sections of metal.

The construction of my present machine whereby this adjustability of the concave is effected may be described as follows: The concave sections all rest in grooved segments or frames C.

These segments are pivotally attached to the frame at their front ends, and at their rear ends are supported and attached to the frame by a slot-and-pin arrangement, C'. A rod, D, carrying cams D', operates to raise and lower the concave. This rod is journaled in the frame, 95 100

and terminates at either one or both of its ends in a crank or bent portion upon the outside of the machine, and this crank or bent portion of the rod may be associated with an adjusting rack, D², or any other suitable device, whereby the rod and its cams D' may be maintained in any position, and thus hold the concave at any adjustment.

E is a rotary deflector and beater. This device is journaled to the frame of the machine, and is located above the shaker F and immediately in the rear of the thrashing-cylinder. The function of the device E is to arrest the straw that is thrown against it from the thrashing-cylinder, and at the same time to act as a deflector to deflect the straw down to the shaker F and with its blades to beat, thereby assisting in separating, the grain.

G G are two rotary beaters, journaled to the frame of the machine and placed over the shaker F in the rear of the deflecting-beater E. The beaters G G serve to agitate the straw, and thus assist in a thorough separation of the grain.

I do not in my present invention claim anything novel in the construction of the shaker F. It is provided preferably with toothed bars, and is made open and given a longitudinal oscillating motion, so that the straw is carried from the thrashing-cylinder to the tail of the shaker by said oscillating movement, while the grain, as it is separated from the straw, drops down through the table to the mechanism beneath.

H is the blast-fan, surrounded with the usual air-casing, the air from which is conducted through one or more pipes, or casing H', beneath the shaker F, where it is discharged up through the shaker, thus assisting not only in the agitation of the straw, but in the separation of the grain therefrom. So far as I am aware this feature is novel in grain-separators.

K is the riddle-fan, the air from which is employed for separating chaff from the grain as it is sifted through the screens and riddles of the shoe. It will be seen that the lower portion of the casing of the fan K projects below the frame A, and as this casing is made of light material it would be apt when thus projecting to be broken or damaged in moving or shipping the machine. I therefore make the lower section, K', of the fan-casing removable. When the machine is in use this section is placed in its position and buttoned or otherwise secured; but when the machine is to be moved said section is taken off and the fan K turned so that its wings shall not project below the frame A. When thus arranged the machine may be moved from place to place without danger of injury to the fan K or its casing.

L is the lower table or receiving-platform, upon which the main portion of the grain falls as it is separated and sifted through the shaker F. This table, like the shaker F, is given a longitudinal reciprocating or shaking motion,

and is inclined downward toward the rear of the machine. It terminates in a bent or deflected portion, L'. This end L' of the table L comes down very close to the upper riddle or distributor, M, of the shoe. The table or platform L has a motion more extended and rapid than the motion of the shoe which carries the distributor M, therefore the end L' will have a limited movement over the surface of the distributor. By this construction and operation the end L' of the platform L performs the function of pushing the heavier portion of the chaff down over the distributor M until it is fairly subjected to the action of the blast of 75 the fan K.

I come now to a description of the shoe and riddles of my machine.

The effectiveness of this portion of my separator results from the construction and arrangement of its riddles and the manner in which the air blast from the fan K is thereby allowed to act. The grain, as it is delivered to the shoe from the table or platform L, is first received upon the distributor M. This distributor is carried by the shoe and given with it an endwise oscillating motion. It is constructed from corrugated metal. These corrugations are perforated only upon their faces that present from the end of the platform L. This method of perforating the distributor effects two results: First, the straw and chaff, as they are forced and blown toward the tail of the machine, are not liable to enter the perforations; second, the perforated faces of the distributor present toward the fan K in such a manner that air is driven directly through them, thus blowing off the chaff and straw from the distributor to the tail of the machine. Meanwhile the grain falls down through the 90 perforations of the distributor to the screen O and the floor P, where it is finally discharged into any suitable conveyer or receiver.

On account of the construction of the distributor M, already alluded to, it will be seen 110 that it presents a solid and unbroken surface in the direction that the straw and chaff are driven over it, while in an opposite direction it is thoroughly perforated, to admit of the passage of air and the falling of the grain to the 115 riddles beneath.

Q is a screen of woven wire, which is attached as an extension of the distributor M. This screen Q is employed when the machine is used for separating small seed, such as flax, 120 timothy, &c. It is not necessary when the machine is employed for thrashing grain.

What I claim is—

1. In a thrashing-machine, the combination, with the straw-shaker, of a blast-fan, the air-casing, and the pipe supported by the frame of the machine below the shaker for sending a blast up through it, substantially as set forth.

2. The combination, with the riddle M, of the grain-table L, having its rear end imperforate and downwardly curved at L', the parts being arranged, as described, to cause the down-

wardly-projecting portion L' to move over and in close proximity to the upper end of the ridge M, substantially as set forth.

3. The combination of a toothed cylinder 5 and concave sections arranged to form a central feed-opening and formed with ribs converging upwardly from said opening, a concave section over the cylinder provided with ribs converging rearwardly, and a concave section 10 in rear of the cylinder arranged to leave a dis-

charge-opening at each end and formed with ribs diverging toward said discharge-openings, substantially as set forth.

In testimony whereof I have signed my name to this specification in the presence of two 15 subscribing witnesses.

ALLEN A. RUSSELL.
